DESIGN FOR A BIRD BATH

Herbert G. Hoefler, New Haven, Conn., assignor to The Andrew B. Hendryx Company, New Haven, Conn., a corporation of Connecticut

Application April 6, 1934, Serial No. 51,323

Term of patent 14 years

To all whom it may concern:

Be it known that I, HERBERT G. HOEFLER, a citizen of the United States, residing in New Haven, in the county of New Haven and State of Connecticut, have invented a new, original, and ornamental Design for a Bird Bath, of which the following is a specification when taken in connection with the accompanying drawing:

Fig. 1 is a side elevation of a bird bath showing my new design;

Fig. 2 is a front end view;
Fig. 3 is a top plan view; and
Fig. 4 is a rear end view.

I claim:

The ornamental design for a bird bath substantially as shown.

HERBERT G. HOEFLER.
